UNITED STATES PATENT OFFICE.

BELLE C. ESKRIDGE, OF HOUSTON, TEXAS.

DESIGN FOR A DOLL.

49,056.

Specification for Design. Patented May 16, 1916.

Application filed March 24, 1916. Serial No. 86,519. Term of patent 7 years.

To all whom it may concern:

Be it known that I, BELLE C. ESKRIDGE, a citizen of the United States, residing at Houston, in the county of Harris and State of Texas, have invented a new, original, and ornamental Design for a Doll, of which the following is a specification, reference being had to the accompanying drawing, forming part thereof.

The figure is a front view of a doll, showing my new design.

I claim:

The ornamental design for a doll, as shown.

BELLE C. ESKRIDGE.

Witnesses:

ANNIE L. CARY,
W. B. SHELF.
